KEY HOLDER OR SIMILAR ARTICLE

Henry J. Modrey, Newark, N. J.

Application June 2, 1949, Serial No. 3,011

Term of patent 7 years

(Cl. D17—14)

To all whom it may concern:

Be it known that I, Henry J. Modrey, a British subject, residing in the State of New Jersey, city of Newark, county of Essex, have invented a new, original, and ornamental Design for a Key Holder or Similar Article, of which the following is a specification, reference being had to the accompanying drawing, forming a part thereof.

In the drawing:

Fig. 1 is a side elevational view of a key holder or similar article, showing my new design;

Fig. 2 is an elevational view at right angles to the position of Fig. 1.

I claim:

The ornamental design for a key holder or similar article, as shown.

HENRY J. MODREY.
